US00D873283S

(12) **United States Design Patent** (10) Patent No.: **US D873,283 S**
Bradley et al. (45) Date of Patent: **** Jan. 21, 2020**

- (54) **COMPUTERIZED DISPLAY DEVICE WITH GRAPHICAL USER INTERFACE FOR TARGET HUMIDITY**
- (71) Applicant: **D-M-S Holdings, Inc.**, West Des Moines, IA (US)
- (72) Inventors: **Samuel Bradley**, Mundelein, IL (US); **Fernando Sanchez**, Berwyn, IL (US); **Hao Chen**, Shanghai (CN)
- (73) Assignee: **D-M-S HOLDINGS, INC.**, West Des Moines, IA (US)
- (**) Term: **15 Years**
- (21) Appl. No.: **29/612,427**
- (22) Filed: **Aug. 1, 2017**
- (51) LOC (12) Cl. **14-04**
- (52) U.S. Cl. **USPC D14/486**
- (58) **Field of Classification Search**
USPC D14/485-495
CPC G06F 3/048; G06F 3/0481; G06F 3/0482; G06F 3/04842; G06F 3/04817

(57) **CLAIM**

The ornamental design for a computerized display device with graphical user interface for target humidity, as shown and described.

DESCRIPTION

The FIGURE is a front view of a computerized display device with graphical user interface for target humidity of Applicant's design.

The broken lines showing the computerized display device, portions of the graphical user interface, and horizontal and angled patterns form no part of the claimed design.
